UNITED STATES PATENT OFFICE

PETER CLAUSEN, OF MISSION, SOUTH DAKOTA

GAME APPARATUS

Application filed April 30, 1929. Serial No. 359,257.

This invention relates to game apparatus and more particularly to a game apparatus for use in conjunction with pool tables to enable playing thereon a game which might 5 well be termed pool-table golf.

An important object of the invention is to produce an attachment of this character which may be very readily applied to the bed of the table, and which enables use of normal accessories of the table and normal portions of the structure thereof in completing the game apparatus.

A further and more specific object of this invention is to produce an apparatus, combined with the pockets and the usual balls and cues of pool table apparatus to provide a semblance of a golf course arranged in such fashion that the pockets of the pool table form a portion of the holes of the course.

These and other objects I obtain by the apparatus shown in the accompanying drawings, wherein for the purpose of illustration I have shown a preferred embodiment of my invention, and wherein:

Figure 1 is a plan view of a pool table equipped with game apparatus constructed in accordance with my invention, portions of the rails of the table being broken away;

Figure 2 is a section on line 2—2 of Figure 1;

Figure 3 is a section on line 3—3 of Figure 1;

Figure 4 is a section on line 4—4 of Figure 1;

Figure 5 is a section on line 5—5 of Figure 1.

Referring now more particularly to the drawings, the numeral 10 generally designates the usual pool table bed, and 11 the pockets thereof of which, as is well known, there are six arranged, four at the corners of the table and two at the centers of the sides thereof.

In accordance with my invention I provide a sheet 12, which may be conveniently formed from papier mâché, linoleum or any suitable substance, and which should have a fair thickness for a purpose hereinafter to appear. The upper surface of this sheet has defined thereon as by painting or the like,

certain hazard areas, these areas in the present instance including a highway 13, a lake 14, and a river 15. Each hazard representation applied to the surface of the sheet may have applied thereto penalty indicia 16 designating a prescribed penalty attending the resting of a player's ball thereon.

In addition to the hazard representations painted or otherwise produced flatly upon the sheet, I also provide hazard representations which are attached to the sheet and which project above the surface thereof, thus constituting actual hazards which must be overcome by the ball of the player.

These representations include hills or mounds 17, a pit 18, and a bridge 19. Each of these elements is preferably secured to the sheet by tangs 20 upon the under surface thereof, also, of course, any other suitable detachable fastening means might be employed, such as snap fasteners. The hill representations 17 preferably constitute a body which is centrally peaked, the pit representation 18, a body having a relatively flat central portion 21, and having disposed at its opposite side edges low and high ribs or flanges 22 and 23. The bridge representation is merely constructed in the semblance of the side rails of a bridge. I further provide a representation of a keep-to-the-right dummy 24, which is disposed upon the highway representation 16.

The sheet bears indicia 25 which in the applied position thereof opposes the pool table pockets, serially numbering the same, as the holes in a golf course. Additional holes are provided by securing to the sheet trunconical bodies 26, the upper surfaces of which are provided with shallow depressions 27 in which a ball may come to rest. These additional holes are likewise numbered. Adjacent each hole I define a small area 28 providing a tee from which the ball may be driven after the hole has been successfully played, a starting tee 29 being provided and suitably labeled as by the letter S from which play may be initiated.

In disposition of the hazard representations which constitute actual hazards against which the ball when striking will be deflected,

as is the case with hazards 17, 18, 19, and 24 and in placing the additional holes 7 to 9, these devices can be arranged so that direct play is interfered with and a successful shot ⁵ can only be made by banking.

- For example, between the starting tee S and the hole No. 1, a hole representation may be interposed; between the green of hole No. 1 and green No. 2, the pit 18 may be disposed; ¹⁰ between the tee of hole No. 2 and hole No. 3, a second hole representation may be disposed; between the green of hole No. 3 and hole No. 4, the bridge representation may be disposed, and etc. In connection with the ¹⁵ bridge element it is pointed out that side members thereof are spaced apart, so that a skillfully shot ball may pass therebetween and enter hole No. 4, thus making it possible to make a hole in one by skillful play.
- ²⁰ In playing the game, the objective is exactly that of the game of golf i. e., to complete the round of the course while using the smallest possible number of strokes. The counting is made in exactly the same manner ²⁵ as in the game of golf, and when the ball of any player comes to rest upon a hazard area defined upon the sheet, as at 13, 14 or 15, the player is penalized a number of strokes indicated by the penalty indicia 16, where the ³⁰ penalty may be inflicted when the ball of a player enters any other hole than that to which his play is directed.

It will be obvious that apparatus of this character may be very readily and cheaply ³⁵ manufactured, readily applied to and removed from the pool table, and will not in any manner interfere with the normal use thereof. Since no extra apparatus is necessary beyond the sheet 12 and the hazard representations, the cost of adding the game will ⁴⁰ be very low to pool table owners.

The arrangement illustrated being entirely arbitrary and capable of considerable modification, I do not wish to be understood as limiting myself to this arrangement except as ⁴⁵ hereinafter claimed.

I claim:—

1. Apparatus for playing a game simulating golf upon pool tables, comprising in combination with a pool table including the usual bed and pockets a spherical member, a sheet superimposed upon said bed and covering the same having adjacent each pocket of the table an indicium identifying the pocket as one of successive holes of a golf course the sheet being further provided with suitably designated areas associated with each hole and from which a ball must be played to the hole, the sheet having further produced ⁵⁰ thereon hazard areas penalizing the player when his ball comes to rest thereon.
2. Apparatus for playing a game simulating golf upon pool tables, comprising in combination with a pool table including the usual ⁵⁵ bed and pockets a spherical member, a sheet

superimposed upon said bed and covering the same having adjacent each pocket of the table an indicium identifying the pocket as one of successive holes of a golf course the sheet being further provided with suitably designated areas associated with each hole and from which a ball must be played to the next hole, the surface of the sheet having elevated portions the tops of which are provided with depressions in which a ball may settle, ⁷⁰ said portions being successively designated as further holes of the course, the sheet having further produced thereon hazard areas penalizing the player when his ball comes to rest thereon. ⁷⁵

3. Apparatus for playing a game simulating golf upon pool tables, comprising in combination with a pool table including the usual bed and pockets a spherical member, a sheet superimposed upon said bed and covering the same having adjacent each pocket of the table an indicium identifying the pocket as one of successive holes of a golf course, the sheet being further provided with suitably designated areas associated with each hole and from which a ball must be played to the next hole, and obstacles projecting upwardly from the face of the sheet preventing or rendering difficult direct play of a ball from an area to the associated hole. ⁸⁵ ⁹⁰

4. Apparatus for playing a game simulating golf upon pool tables, comprising in combination with a pool table including the usual bed and pockets a spherical member, a sheet superimposed upon said bed and covering the same having adjacent each pocket of the table an indicium identifying the pocket as one of successive holes of a golf course, the sheet being further provided with suitably designated areas associated with each hole and from which a ball must be played to the next hole, and obstacles projecting upwardly from the face of the sheet preventing or rendering difficult direct play of a ball from an area to the associated hole, said obstacles being detachably secured to the sheet. ¹⁰⁰ ¹⁰⁵ ¹¹⁰

In testimony whereof I hereunto affix my signature.

PETER CLAUSEN.
